UNITED STATES PATENT OFFICE.

FRANK PAUL NOBIS, OF PHILADELPHIA, PENNSYLVANIA.

STOPPER-EXTRACTOR.

No. 825,929.

Specification of Letters Patent.

Patented July 17, 1906.

Application filed September 19, 1903. Serial No. 173,893.

To all whom it may concern:

Be it known that I, FRANK PAUL NOBIS, a citizen of the United States, residing at Philadelphia, in the State of Pennsylvania, have 5 invented a new and useful Stopper-Extractor, of which the following is a specification.

This invention relates to a device intended for the use of waiters; and the object of the same is to provide a device by means of which 10 crimped metal caps can be readily removed from bottles.

My invention consists in the novel features of construction and combination of parts hereinafter described, particularly pointed 15 out in the claim, and shown in the accompanying drawings, in which—

Figure 1 is a perspective view showing the mode of using my device. Fig. 2 is a perspective view of my device, showing same 20 closed. Fig. 3 is a longitudinal section through the handle, showing the bottle-opening device opened out. Fig. 4 is a section on the line 4 4 of Fig. 3.

In constructing a device of the kind shown 25 I employ a handle A, formed, as is usual, of two side pieces and reduced in width throughout a portion of their length, as shown at A'. A leaf-spring A², such as is commonly used in pocket-knives, is arranged in the handles A, 30 and between the said handles is pivoted a dull blade C, the blade having a shoulder formed thereon adjacent its pivotal point, and this shoulder is engaged by the free end of the spring A², thereby locking the blade C 35 in its open position. The blade C is slightly curved toward its free end, and the blade C is comparatively thick, as shown in the cross-sectional view of Fig. 4. To opposite sides of the blade C are secured depending arms C², 40 arranged parallel to each other and at right angles to the blade C and at a distance from

its free end slightly greater than the diameter of the average metal cap employed upon bottles. The blade C is, however, preferably of such length that the arm C² will be nearer 45 to the free end of the blade than to its pivotal point. The lower portions of the arm C² are bent forwardly at right angles to the said arms and substantially parallel to the adjacent portion of the blade C. When the blade 50 C is opened out, the bent end portion C³ of the arms C² can be engaged with the lower edge of a metal cap, and the slightly-curved portion of the blade C will extend transversely across the cap and will bear upon the 55 edge of the cap diametrically opposite the portion engaged by the ends of the arms C². A considerable leverage will be gained, and an upward pull upon the handle A will remove the metal cap or stopper from the 60 bottle.

Having thus fully described my invention, what I claim as new, and desire to secure by Letters Patent, is—

In a bottle-cap remover, the combination 65 with a handle comprising two side members each having a portion reduced in width, of a curved flat shank pivoted between said side members, and short arms secured oppositely each to one side of the said shank at a point 70 about midway of its length and extending transversely at one side of said shank with hooked ends bent toward the free end of the shank, said arms positioned so that the ends rest on the reduced portions of the handles 75 when the shank is folded to lie between them, whereby the shank can be easily grasped by the hand.

FRANK PAUL NOBIS.
